(57) **CLAIM**

The ornamental design for an audio speaker cabinet, as shown and described.

DESCRIPTION

FIG. 1 is a front perspective view of an audio speaker cabinet, showing my new design.

FIG. 2 shows a rear perspective view thereof.

FIG. 3 is a front view thereof.

FIG. 4 is a rear view thereof.

FIG. 5 is a right side view thereof, and the left side view being a mirror image thereof; and,

FIG. 6 is a top plan view thereof.

The broken line portions show unclaimed subject matter only and form no part of the claimed design.
